UNITED STATES PATENT OFFICE.

JAMES BARLOW AND JAMES MOSES, OF TRENTON, NEW JERSEY.

DESIGN FOR A SET OF CHINAWARE.

SPECIFICATION forming part of Design No. 12,350, dated July 12, 1881.

Application filed January 4, 1881. Term of patent 3½ years.

To all whom it may concern:

Be it known that we, JAMES BARLOW and JAMES MOSES, of Trenton, in the county of Mercer and State of New Jersey, have invented 5 a new and original Design for Sets of Chinaware, of which the following is a full, clear, and exact description, reference being had to the accompanying drawings, which form a part of this specification.

10 Our invention relates to a new and ornamental design for such sets as are hereinafter described and shown.

In the accompanying drawings, Figure 1 is a side view of an oval covered dish provided 15 with an upper ornamental and ornamented part or neck, and, with feet and cover and handles, embodies or contains our design. Fig. 2 is a top view of the same. Fig. 3 is an enlarged view of the end of one of our handles; and 20 Fig. 4 is an enlarged top view of one of said handles.

In Fig. 1, A represents the body of the dish; B, its cover; C, the handles, and D the feet.

In shaping the body of the dish, instead of 25 giving the sides of the dish the curve up to the top of the dish, we curve the sides in somewhat more rapidly, and surmount such curved sides with a straight lined or sided neck or upper part, E. Upon and around this upper part we 30 place the flutings E', extending from near the top of the dish down to or near to the curved sides. The number and size of these flutings and their extent up or down are immaterial, though we preferably arrange and extend them as shown. This neck or upper part is 35 not exactly oval in section, but has in it four contractions or indentations, two of which are shown at E², Fig. 1. The body of the dish, instead of being provided with the ordinary foot 40 composed of a ring or flange extending all the way around the bottom, has four ornamental- 45 ly-shaped feet, D, placed one upon each side of the bottom and one at each end thereof.

The cover of the dish is of the usual shape, 45 except that its outline, instead of being oval, has four indentations or depressions (shown at E³, Fig. 2,) extending some distance into the cover and gradually merging into the oval shape of the top of the cover. These indentations correspond in relative position with the

depressions in the neck or upper part of the dish.

The general shape of the handles, both of the vessel and of the cover, is shown more clearly in Fig. 4. The handle is an imitation 55 of turned work, (but actually molded in making,) having the central circular projection, F, the ogee G, and the end part or prolongation, H. Around this end part, H, is arranged in a direction parallel with the axis of the handle 60 half-round ribs H', as shown at Fig. 3. At the end of the handle is placed the daisy I, with the central projection, K, representing the bulbous part of the flower. The whole is mounted upon the pedestals L. 65

While the description has reference to dinner sets only, the design can be applied to tea and toilet sets.

What we claim as our invention is—

1. A design for a dish, consisting of the 70 curved-sided part A, the surmounting straight-sided part or neck E, the flutings E', the indentations E², the ornamental-shaped feet D, the cover B, with indentations E³, and the handles C, each shaped and all combined substantially as herein shown and described.

2. A design for a dish, consisting of the curved-sided part A, provided with the ornamental-shaped feet D, and the surmounting straight-sided part E, provided with the flutings E' and indentations E², all substantially as herein shown and described. 80

3. A design for a dish, consisting of the curved-sided part A, provided with the ornamental-shaped feet D, and the surmounting straight-sided part E, provided with the flutings E', substantially as shown and described. 85

4. A design for the feet of a dish, consisting of the ornamental-shaped feet D, arranged substantially as shown and described. 90

5. A design for a dish-handle, consisting of the central circular projection, F, the ogee G, the end part or prolongation, H, with its ribs H', the daisy I, and pedestals L, all substantially as shown and described.

JAMES BARLOW.
JAMES MOSES.
